COOKING RANGE

Charles M. Mayer, Mansfield, and Earl S. Pollock, Lexington, Ohio, assignors to The Tappan Stove Company, Mansfield, Ohio, a corporation of Ohio

Application March 16, 1955, Serial No. 35,074

Term of patent 14 years

(Cl. D81—4)

The figure is a perspective view of a cooking range showing our new design.

The left hand side of the cooking range, not shown in the drawing, is substantially the same as the illustrated right hand side thereof.

We claim:

The ornamental design for a cooking range, as shown and described.
